UNITED STATES PATENT OFFICE.

ANDREW J. HOLT, OF MARYVILLE, MISSOURI.

UNLOADING APPARATUS.

1,203,620.

Specification of Letters Patent. Patented Nov. 7, 1916.

Application filed June 26, 1915. Serial No. 36,517.

To all whom it may concern:

Be it known that I, ANDREW J. HOLT, a citizen of the United States, residing at Maryville, in the county of Nodaway and State of Missouri, have invented certain new and useful Improvements in Unloading Apparatus, of which the following is a specification.

This invention relates to improvements in apparatus for unloading or discharging the contents of vehicles directly into bins or other receptacles, thereby eliminating the usual manual labor in effecting the transfer.

In the transportation and handling of articles or commodities in loose bulk, such as grain and the like, it is desirable that the vehicle containing the same be discharged quickly and easily into the desired container or receptacle. While wagons with dumping bottoms may fulfil this requirement in some respects, it is not always convenient to utilize the same.

Accordingly, to provide for removing the contents of a wagon of the ordinary type having a removable or hinged end gate, such as are more commonly found in farm use and general drayage, the present invention contemplates a novel device having means for permitting the entire body of the wagon to tilt rearwardly to discharge its contents.

Primarily, the invention has in view the provision of a turn-table device that is mounted in a housing or shed and adapted to be turned to any desired position to be dumped, and then turned so that the vehicle may leave the platform and thus reset the tilting section that had been released to effect the unloading. While the invention in this form is especially adapted for farm use, in connection with the unloading of grain and stock feed into bins or storage receptacles, it is susceptible to a wide range of other uses where the distribution of wagon contents as a whole is desirable to save time and labor.

A further object of the invention is to provide a novel and practical tilting wheel supporting means, and a simple retaining and releasing device therefor.

A further and more general object is to provide a construction that is not only economical and reliable, but simple, substantial and easy to operate.

With the above and other objects in view which will more readily appear as the na-

ture of the invention is better understood, the same consists in the novel construction, combination and arrangement of parts hereinafter more fully described, illustrated and claimed.

A preferred and practical embodiment of the invention is illustrated in the accompanying drawings, in which—

Figure 1 is a perspective view of the framework of the housing, showing the application of the present invention. Fig. 2 is a top plan view of the construction shown in Fig. 1 with the compartments or bins designated by dotted lines. Fig. 3 is a vertical sectional view on the line 3—3 of Fig. 2 showing the turn-table device in normal position. Fig. 4 is a vertical sectional view taken at one side of the wheel supporting members with the turn-table turned and the tilting wheel supporting members released. Fig. 5 is a detail end elevation of the turn-table platform showing the novel means for retaining the tilting members in place. Fig. 6 is an enlarged detail sectional view showing the tilting wheel supporting members more clearly.

Similar reference characters designate corresponding parts throughout the several figures of the drawings.

In carrying out the present invention, it is proposed to construct the housing H, so that any desired number of storage bins B or receptacles may be provided. However, for the purposes of illustration, the present drawings show an octagonal form of housing consisting of the outer vertical frame members 1, and the inner turn-table supporting posts or struts 2, which may be radially connected in any suitable member by means of partition walls to form receptacles of the desired height and capacity.

In order to more clearly show the novel features of the present invention, the roof R of the housing H is shown by dotted lines, and the external siding has been omitted. Thus, it may be observed from the several figures that the interior of the housing H is provided with a continuous path or footway 3 which extends entirely around the housing, and over the bins or receptacles B. The housing H is further provided at one side with a suitable runway 4 which permits teams or vehicles to enter the housing and be positioned on the turn-table device designated generally as T, and arranged concentrically with the bins or re-

ceptacles B. This turn-table device essentially includes a turn-table platform 5 which is supported upon the plurality of transverse beams 6, and the longitudinal beams 7 which carry a plurality of truck members 8 having the wheels 9. Upon the top of the centrally arranged turn-table supporting posts 2 is secured a circular track member 10, upon which the wheels 9 of the turn-table bear. It will thus be obvious that the turn-table may be turned or rotated upon the trackway 10 by means of hand levers 11 secured to the opposite sides of the turn-table platform 5.

15 One end of the turn table platform carries oppositely disposed guard members 12 forming a protecting stall for the draft animal, and the floor of the opposite end of the platform is formed with the spaced parallel 20 open end slots 13, which are of sufficient width to accommodate the tilting wagon supporting members 14 that are made wide enough to accommodate vehicles of slightly varying wheel gage. These tilting wagon 25 supporting members 14 are preferably pivoted at one side of their center as at 15 on a pivot spindle 16 journaled in the oppositely disposed longitudinal beam members 7 of the platform. Normally, these members 30 14 are held in such a position that their upper surface is flush with the face of the platform 5, by means of a retaining device 17. By reference to Fig. 5, it will be observed that this retaining device 17 is in the 35 form of a single rocking bar which is formed adjacent each end with downwardly disposed holding loops 18, normally receiving and holding the free ends of the members 14. This bar 17 is rotatably held to 40 the platform 5 by means of suitable eyes 19 and is provided at one end with an offset handle or crank member 20. Accordingly, as the slots 13 are opened at their rear ends, and the loops 18 of the operating bar 17 enter 45 gage and support the rear ends of the members 14 under normal conditions, it will be apparent that when the handle 20 of the operating bar is moved downwardly toward the floor of the turn-table, the loops 18 will 50 be swung upwardly and clear the ends of the members 14 thus permitting the same to tilt upon the pivot 16.

From the foregoing description, it will be 55 apparent that a vehicle may be driven onto the turn-table device T, while the same is in its normal position as shown in Fig. 3, that is, when the tilting members of the platform are disposed adjacent the runway 4, so that the front and rear wheels of the vehicle will 60 both rest upon the said tilting members 14. While in this position, the turn-table device is rotated so that the rear end of the vehicle is directly above a bin or receptacle into

which the contents of the wagon are to be discharged, and then the lever device 17 is 65 turned by means of the handles 20 so that the rear end of the members 14 will be released, thus permitting the entire body of the vehicle to tilt rearwardly. After the contents of the wagon have been discharged, 70 the turn-table may be rotated so that the front end, namely, that having the guard members 12, will be adjacent the runway 4, so that the vehicle may be driven off of the platform, and thus reset the tilting members 75 4, as the wheels thereof move to the opposite side of the pivot points 15. The locking bar 17 is then turned so that the loops 18 again engage the ends of the members 14, relocking the same in their normal position. The 80 turn-table may be then returned to normal position, that is, so that the end thereof having the tilting members is adjacent the runway 4, and ready to receive another vehicle.

Without further description, it will be 85 readily apparent to those familiar with the art, that minor changes in the details of construction may be resorted to without departing from the spirit of the invention or scope of the appended claims.

90 I claim:

1. In an unloading apparatus, the combination of a housing comprising a framework including an outer circular series of supporting members, an inner circular series of supporting members so arranged with respect to the outer series of supporting members as to form the framework of a circular group of storage compartments, a circular trackway mounted on said inner supporting 95 members, and a vehicle supporting turntable device mounted on said circular trackway within the housing and concentric to said compartments.

2. In an unloading apparatus, the combination of a housing comprising a framework including an outer circular series of supporting members, an inner circular series of supporting members so arranged with respect to the outer series of supporting members as to form the framework of a circular group of storage compartments, an inclined 100 runway extending into the housing, a manway supported by said outer series of supports over said storage compartments, a circular trackway mounted on said inner supporting members, and a vehicle supporting turntable device mounted on said trackway concentric to said compartments, and having load-dumping means.

105 110 115 120 In testimony whereof I hereunto affix my signature in the presence of two witnesses.

ANDREW J. HOLT.
